GLUTARIMIDES FOR REDUCING THE NUMBER
OF FETUSES IN MATED OR IMPREGNATED
FEMALE MAMMALS
Bernard George Steinetz, Jr., Mountain Lakes, N.J., as

3 Claims

ABSTRACT OF THE DISCLOSURE

Pharmaceutical compositions comprising an effective amount of an α -(4-aminophenyl)- α -lower alkyl - glutarimide, a salt or N-lower alkanoyl derivative thereof and a pharmaceutical excipient, are agents for reducing the number of fetuses in mated or impregnated female mammals.

BACKGROUND OF THE INVENTION

Of the α -(4 - aminophenyl)- α -lower alkyl-glutarimides disclosed in U.S. Pat. No. 2,848,455, the α -ethyl derivative, i.e. aminoglutethimide, has already been used at low dosage levels, e.g. in the form of 125 and 250 mg. tablets, as a long-term anticonvulsant which, alone or particularly as an adjunct, controls seizures in most forms of epilepsy, even in cases refractory to other therapeutic agents. Surprisingly, it was found that said glutarimides exert at higher dosage levels, but applied in a much shorter period of time, a fetal reducing effect in female mammals, which is not accompanied by the alleged adverse side-effects described for the long-term treatment.

SUMMARY OF THE INVENTION

The present invention concerns and has for its object the provision of a pharmaceutical composition comprising essentially (a) an effective amount of a compound corresponding to Formula I

(I)

in which R is lower alkyl and X is hydrogen or lower alkanoyl, or a therapeutically acceptable acid addition salt thereof, and (b) a pharmaceutical excipient; as well as of a new method of reducing the number of fetuses in mated or impregnated female mammals with said active compounds of Formula I, advantageously in the form of orally applicable pharmaceutical compositions thereof.

DESCRIPTION OF THE PREFERRED EMBODIMENTS

The active ingredients of the compositions claimed herein are described in U.S. Pat. No. 2,848,455. Preferred is the α -(4-aminophenyl) - α - ethyl-glutarimide (aminoglutethimide). Said ingredients can be used in the free form or in the form of therapeutically acceptable acid addition salts thereof. Preferred salts are those of inorganic acids, e.g. hydrochloric, hydrobromic, sulfuric, nitric, perchloric or especially phosphoric acid, but also those of organic acids, such as carboxylic or sulfonic acids, e.g. formic, acetic, propionic, succinic, glycolic, lactic, malic, tartaric, citric, ascorbic, maleic, hydroxymaleic, pyroracemic, phenylacetic, benzoic, 4 - aminobenzoic, anthranilic, 4-hydroxybenzoic, salicylic, aminosalicylic, embonic, nicotinic, methanesulfonic, ethanesulfonic, hydroxyethanesulfonic, ethylenesulfonic, benzenesulfonic, halogenbenzenesulfonic, toluenesulfonic, naphthalenesul-

2

fonic or sulfanilic acid, methionine, tryptophan, lysine or arginine.

The compositions according to the invention are applied to female mammals at a dosage level corresponding to about 20 to about 200 mg./kg. of said glutarimides, preferably between about 50 and 150 mg./kg., per day or 8-16 hour period, either in a single or advantageously in multiple dosage units from preferably two to three times, up to about four to six times, either prior or after conception, for example, during the first quarter of gestation.

Said properties of the compositions according to this invention can be demonstrated, for example, in animal tests, using mammals, e.g. rats, hamsters or rabbits, as test objects. Such tests can be performed by administering said active glutarimides in the form of aqueous solutions or suspensions by stomach tube to said test animals at any of the first 9 days of pregnancy in a dosage range between about 20 and 200 mg./kg./day, or preferably 8 hours, in up to 3 consecutive doses. On day 11 the animals are sacrificed and their uterus compared with that of control animals. Thus, for example, when a composition of aminoglutethimide, the characteristic compound of the compositions according to this invention, is administered in the above manner orally or subcutaneously as a simple or acetate-buffered aqueous solution of the phosphate thereof, to rats at one to three consecutive dosages of about 100 to 200, preferably 150 mg./kg./8-24 hours, following the 9th day of pregnancy, no or very few fetuses are found in the uterus of the medicated animals, as compared with an average of 11 found in that of the control animals. In another test system, using rabbits, a single dose of an aqueous aminoglutethimide phosphate solution of about 100 mg./kg., markedly reduced the secretion of progesterone by the ovary. This is estimated by the continuous withdrawal of blood from the ovarian vein, starting about $\frac{1}{2}$ hour prior to drug administration and continuing for a total of $1\frac{1}{2}$ hour. During this time, the blood-progesterone content is monitored by standard methods and falls to a level below 50% of the control value. Similar results are obtained from either pregnant or non-pregnant animals.

Accordingly, said compositions of the invention are enterally or parenterally, advantageously orally applicable agents. Preferred are tablets and gelatin capsules comprising the active ingredient together with (a) diluents, e.g. lactose, dextrose, sucrose, mannitol, sorbitol, cellulose and/or glycine, (b) lubricants, e.g. silica, talcum, stearic acid, its magnesium or calcium salt and/or polyethylene-glycol, for tablets also (c) binders, e.g. magnesium aluminum silicate, starch paste, gelatin, tragacanth, methylcellulose, sodium carboxymethylcellulose and/or polyvinyl-pyrrolidone, if desired, (d) disintegrants, e.g. starches, agar, alginic acid or its sodium salt, enzymes of the binders or effervescent mixtures and/or (e) adsorbents, colorants, flavors and sweeteners. Injectable compositions are preferably aqueous isotonic solutions or suspensions, and suppositories are advantageously fatty emulsions or suspensions. They may be sterilized and/or contain adjuvants, such as preserving, stabilizing, wetting or emulsifying agents, solution promoters, salts for regulating the osmotic pressure and/or buffers. Said pharmaceutical compositions may also contain other therapeutically valuable substances. They are prepared according to conventional mixing, granulating or coating methods respectively, and contain about 10 to 90%, preferably about 20 to 80%, of the active ingredient, or advantageously about 0.5 to 1 g. thereof per dosage unit.

The method of treatment according to the invention consists in administering to a mated or impregnated female mammal a single, or preferably multiple dose of about 20 to about 200 mg./kg. preferably about 50 to about 150

mg./kg./8-24 hours of said active α -(4-aminophenyl)- α -lower alkylglutarimide, its lower alkanoyl derivative or salt, preferably in the form of the above compositions, advantageously in an orally applicable form, e.g. as tablet, dragée or capsule and advantageously during the first quarter of gestation. For a mammal of about 50 to 70 kg. weight, the administration of about 1 to 2 g. of said glutarimides, especially aminoglutethimide, in single or multiple oral dosage units is preferred. For example, 500 mg. tablets or capsules of aminoglutethimide can be administered to said mated female mammal up to four times during a period of 1.5 to 4 days, in order to reduce the number of fetuses.

The following examples are intended to illustrate the invention and are not to be construed as being limitations thereon.

EXAMPLE 1

Preparation of 1,000 tablets, each containing 500 mg. of the active ingredient:

Formula:	G.
Aminoglutethimide	500.0
Lactose	240.0
67% aqueous sucrose	45.0
Talcum	20.0
Stearic acid	5.0
Magnesium stearate	5.0

Procedure: All the powders are passed through a screen with opening of 1.2 mm. Then the drug substance, lactose and talcum are mixed in a suitable mixer and granulated with the sucrose solution, if necessary, with an additional amount of water. The granulate is dried to a moisture content of about 1-3%, broken on a screen with 0.85 mm. openings, mixed with the stearic acid and magnesium stearate and compressed into tablets using standard concave punches with 12 mm. diameter, uppers bisected.

EXAMPLE 2

Preparation of 1,000 tablets, each containing 0.5 or 1 g. of the active ingredient:

Formula:	Grams		
Aminoglutethimide	500.0	1,000.0	
Wheat starch	140.0	200.0	
Methylcellulose, 100 cps	14.0	20.0	
Colloidal silica	7.0	10.0	
Talcum	32.0	55.0	
Stearic acid	7.0	15.0	
Purified water	q.s.		

5 Procedure: All the powders are passed through a screen with 0.6 mm. openings. Then the drug substance, methylcellulose and silica are mixed well and granulated with a paste of the starch and about 5-6 times the amount of water. The granulate is dried overnight at 35°, broken on a screen with 1.2 mm. openings, mixed with the talcum and stearic acid and compressed into 12 mm. or capsule-shaped tablets, respectively.

What is claimed is:

- 10 1. A method of reducing the number of fetuses in a female mammal, which consists in the administering to a mated or impregnated female mammal a single or multiple enteral or parenteral dose of about 20 to about 200 mg. of a compound corresponding to the formula

15

in which R is lower alkyl, or a therapeutically acceptable acid addition salt thereof, per kg. of the mammal's body weight and per 8 to 24 hours during a period of 1.5 to 4 days of the first 9 days of suspected pregnancy.

25 2. The method as claimed in claim 1, wherein a dose of about 50 to about 150 mg./kg./8-24 hours is administered during a period of 1.5 to 4 days.

30 3. The method as claimed in claim 1, wherein α -(4-aminophenyl)- α -ethyl-glutarimide or a therapeutically acceptable acid addition salt thereof is administered.
